CLAIM

The ornamental design for a meter for an integrated diagnostic test system, as shown and described.

DESCRIPTION

FIG. 1 is a rear-left, perspective view of a meter for an integrated diagnostic test system of the design;

FIG. 2 is a top view of the design of FIG. 1;

FIG. 3 is a rear view of the design of FIG. 1;

FIG. 4 is a left-side view of the design of FIG. 1;

FIG. 5 is a front view of the design of FIG. 1;

FIG. 6 is a right-side view of the design of FIG. 1; and,
FIG. 7 is a bottom view of the design of FIG. 1.

The broken lines in the figures are for illustrative purposes only and do not form part of the claimed invention.

1 Claim, 7 Drawing Sheets
